UNITED STATES PATENT OFFICE.

HORACE HARRIS, OF NEWARK, NEW JERSEY.

SAFETY-POCKET.

Specification of Letters Patent No. 17,573, dated June 16, 1857.

To all whom it may concern:

Be it known that I, HORACE HARRIS, of Newark, in the county of Essex and State of New Jersey, have invented a new and useful Improvement in the Method of Constructing Pockets for Wearing-Apparel, which said invention I designate as "Harris' Protected Pocket;" and I do hereby declare that the following is a full and exact description thereof, reference being had to the accompanying drawings, making a part of this specification, of which—

Figure 1 is a perspective view, the mouth or frame of the pocket being open. Figs. 2 and 4, are views of the frame disconnected from the other part of the pocket, and Fig. 3, a section of a waistcoat, showing therein the adaptation and application of my invention as a guard or watch pocket.

20 The same letters indicate like parts in all the figures.

The pockets now used in wearing apparel are well known to be insecure. The amount of money, valuable papers, and watches, 25 from time to time, either lost or stolen from them, notwithstanding the care taken, amply attest this. The liability of loss is constant, in the cities or on travel they are open to the fingers of the thief, or at home or at leisure, 30 a reclining posture or a change of raiment may involve a loss. To overcome these objections and to construct a pocket in such a manner as that, while it shall be simple, feasible and of little cost, it shall also afford 35 a perfect protection against loss or theft, is the object of my invention.

The nature of my invention consists in inserting strongly between the lining of the garment a pocket guarded about by small 40 chains, to prevent it from being cut out, and having its mouth sewed to a wire spring frame with a spring catch and concealed chain attached thereto in such a manner that although the mouth of the pocket may be 45 sprung together and closed from the outside, it can be opened only by the wearer, and that, by pulling the concealed chain fastened to the said catch.

In the drawing, A is the body of the 50 pocket made of strong linen or other suitable fabric.

B, is the wire frame to which the edges of the mouth of the pocket A, is sewed.

C, is a spring formed on one side of the 55 hinge of the frame and so constructed that the tendency is always to throw the frame

open. The spring C may be formed by twisting the end of one side of the frame B over and then under the other side of the frame, substantially as represented in Fig. 2, or the 60 parts of the frame may be riveted together, and the spring in the frame formed by the arrangement of simply twisting one side of the frame over the other as represented in Fig. 4.

65 D is a catch attached to the frame as represented and held by means of the spring E, in such a position as to seize and retain in a closed position the two parts of the wire frame when brought together, or, when the chain F is drawn, to liberate and permit the spring in the frame to operate and the frame to spring open. The spring E and catch D may be formed of separate parts, riveted together as in Fig. 2, or the said spring and 70 catch may be made of one piece of wire, bent into the required form as represented in Fig. 4. The latter method I think is the best. The chain F, with the ring G, is attached to the catch D, for the purpose of 75 springing the same and is used and adjusted in the manner hereinafter described.

h, h, h, h, are chains attached to the frame B, and bound about and attached to the body of the pocket A, substantially as shown in 80 the drawings and are for the purpose of preventing the pocket from being cut out. The ends of the chains h, h, h, h, running into the garment in different directions (Fig. 3) are for the purpose of preventing the pocket 85 from being cut out, by being cut around it. The wire frame B may be variously constructed and adapted to suit the requirements and convenience of the garment in which it is to be worn, and the mouth of the frame may be formed with the orifices O, O, 90 O, O, (Fig. 3) where the pocket is to be used for a watch, so that the guard chain may not interfere with the closing of the pocket frame. Fig. 3 shows the application 95 100 of my invention to a waistcoat for the purpose of a guard pocket for a watch.

The whole pocket, frame, springs, catch and chains attached thereto are included and concealed in the lining of the garment 105 and the external appearance of the whole is merely that of an ordinary pocket. The chain F is also concealed in the lining, or passed through along the inside of the vest in such a manner that the ring G is brought 110 into a favorable position to be reached by the hand of the wearer. The pocket being

closed no amount of pulling on the guard chain will open it, neither can it be opened in any other manner than by pulling the chain F. But the pocket being open a slight external pressure on it at the point D will close it again, securely locking therein against theft or loss the watch or other valuable of the wearer. The pocket may in like manner be adjusted and applied to any other garment. It may be used in ladies' dresses and may be also so adapted as to take the place of a money belt or for a breast pocket for valuable papers in a coat.

I am aware that Joseph Calton has a

15 patent for "spring, bolt and catch for fastening plates" connected with pockets, but it will be seen that I do not use or claim any of his devices. But

What I claim as my invention, and desire to secure by Letters Patent, is—

20 The wire frame with the spring, C, for throwing it open, constructed in the manner described.

HORACE HARRIS.
